UNITED STATES PATENT OFFICE

154,405

DESIGN FOR A REMOTE-CONTROL CASING
FOR REMOTELY OPERATED DEVICESJoseph A. Lombard, Springfield, Mass., assignor
to Automatic Devices, Incorporated, Springfield,
Mass., a corporation of Massachusetts

Application June 30, 1948, Serial No. 147,313

Term of patent 3½ years

(Cl. D26—14)

To all whom it may concern:

Be it known that I, Joseph A. Lombard, a citizen of the United States, residing at Springfield, in the county of Hampden and Commonwealth of Massachusetts, have invented a new, original, and ornamental Design for a Remote-Control Casing for Remotely Operated Devices, of which the following is a specification, reference being had to the accompanying drawings, forming part thereof.

Fig. 1 is a front elevational view of a remote-control casing for remotely operated devices, showing my new design;

Fig. 2 is a top plan view of the device of my invention;

Fig. 3 is a side elevational view of a remote-control casing for remotely operated devices shown in Figs. 1 and 2.

The rear side of the casing is flat, having the contour of the casing and the rear edges are sharp and non-curving.

I claim:
The ornamental design for a remote-control casing for remotely operated devices, as shown and described.

JOSEPH A. LOMBARD.
